*Thomas L. Lyddy Design for Spur
Assigned to Russell & Erwin Mfg Co*

Des No 1507 Patented Dec 24 1864

Des. 1507

Thomas Layons, of New Britain, Conn.
Assignor to Russell and Erwin
Manufacturing Co. of City of N. York.
Work No. 1507 Letters Patent No. 142, dated Dec. 24, 1861.

The schedule referred to in these Letters Patent and making part of the same.

To all whom it may concern:

Be it known that I, Thomas Layons, of New Britain, in the County of Hartford, and State of Connecticut, have invented or produced a new and original Design for a Horse Spur; and I do hereby declare that the following is a full, clear and exact description of the same, reference being had to the accompanying drawings making a part of this specification, in which -

Figure 1. is a perspective view of a Horse Spur showing my design.

Figure 2. a back view of the same.

Similar letters of reference indicate corresponding parts in the several figures -

This invention consists in having the stock or bow of the Spur provided at its outer side with longitudinal bright or smooth ribs, with corrugated groves between and having the strap loops at the end of the stock provided with a roughened or indented surface, the back part of the stock or bow directly beneath the spur arm having a shell ornament on a roughened or indented ground, the whole forming a choice and neat design.

Des. 1507

A represents the stock or bow of the spur which is of semi-circular form and has a smooth inner surface the outer surface being convex and having three longitudinal ribs a. a. a. at each side between which are recesses or grooves b. having their surfaces corrugated, a corrugated groove c. and corrugated rib d. being at the upper and lower edges of the stock or bow. The strap loops e. at the ends of the stock or bow A. have their outer surfaces corrugated or indented as shown in figure 1.

At the back part of the stock or bow A. there is a raised ornament formed of a shell f. with two scrolls g. g. above it and a small flower g'. at each side, the scrolls being at the base of the arm h. in which the seated wheel i. is placed. The shell f. scrolls g. g. and flowers g'. have a bright surface and are on a corrugated ground, as shown clearly in figure 2. The arm h. has a smooth surface not broken by ornaments of any kind.

Having thus described my invention what I claim as new and desire to secure by Letters Patent is—

The general configuration of the parts herein described to form a new and ornamental design for a spur.

Witnesses.
